LIQUID FUEL STOVE

Ralph W. De Lancey, Meriden, Conn., assignor to
The Miller Company, Meriden, Conn., a corpora-
tion of Connecticut

Application January 27, 1940, Serial No. 316,040

19 Claims. (Cl. 158—94)

The present invention relates to liquid fuel stoves, and is more particularly directed toward liquid fuel stoves of the wick type employing a blower to create a forced draft.

The present invention contemplates liquid fuel stoves of the type above referred to which become automatically extinguished upon cessation of the forced draft produced by the blower.

According to the present invention the supply of air to the burner is interrupted when the blower fails to operate, either because of failure of current supply, or because of insufficient voltage or mechanical difficulties in the blower which cause it to fail to supply air. The air supplied the burner or burners for maintaining proper combustion normally passes through valve mechanism which automatically opens when sufficient forced draft is available and which automatically closes upon cessation of such forced draft. The closing of the valve means shuts off air circulation and the very small amount of air near the lighted wick is soon vitiated and the flame extinguished.

Where the present invention is embodied in a stove with more than one burner it is desirable to provide individual air controlling valves for each burner so that all the valves will be open when the blower is in operation, so that air passes out through each burner (irrespective of whether it is lighted or not) and so that all the valves close simultaneously on cessation of draft thereby making it impossible to induce a natural draft by a burner in operation drawing air in through another burner.

Where the present invention is embodied in a single unit burner the automatic valve may be either between the blower and burner or on the inlet side of the blower.

The present invention also contemplates the provision of improved air diffusing means about the wick tube in the forced draft type of burner, whereby turbulence of the air passing up to the outside of the flame is substantially eliminated.

Other and further objects of the invention will appear as the description proceeds.

The accompanying drawings show, for purposes of illustrating the present invention, three of the many embodiments in which the invention may take form, it being understood that the drawings are illustrative of the invention rather than limiting the same.

In these drawings:

Figure 1 is a diagrammatic side elevational view of a multiple unit burner;

Figure 2 is a vertical sectional view through

a blower and one form of burner suitable for use in multiple unit burners;

Figure 3 is a cross sectional view on the line 3—3 of Figure 2;

Figure 4 is a sectional view similar to Figure 2 showing a modified form of construction;

Figure 5 is a horizontal sectional view on the line 5—5 of Figure 4;

Figure 6 is a vertical sectional view through a single unit pressure burner; and

Figure 7 is a horizontal sectional view on the line 7—7 of Figure 6.

In Figure 1 a motor operated blower is diagrammatically illustrated at 10, a conduit at 11 and two burners 12 and 13 are supplied from the conduit. Figures 2 and 3 illustrate the blower and burner with one form of associated valve mechanism, while Figures 4 and 5 illustrate the blower and burner with another form of valve mechanism.

The blower may include a housing 20 having an air inlet opening 21, a motor 22 and an impeller or fan 23 coupled to the motor shaft 24. The draft created by the blower is passed through an opening 25 into the conduit 11.

A cylindrical member or housing 30 is secured to the top of the conduit and forms an air chest about a wick tube 31. The member 30 carries a collar 32 which extends up above the top of the wick tube. The wick tube is supported by the oil tube 33 and the wick raiser 33' soldered to the housing 30, and is provided with any convenient form of air distributor 34. The upper part of the wick tube carries an air diffuser 35 in the form of a helical coil of wire bent into annular form and secured about the wick tube.

The top of the conduit 11 carries a threaded bushing 36 below the center of the wick tube and extending down through the bottom of the conduit. A vertically adjustable rod 37 is threaded into the bushing. The conduit has a plurality of openings 38 about the shaft 37. These openings form a port through which air can pass from the conduit toward the burner. The port is adapted to be closed by a light-weight, wafer-like member 39 slidably carried on the shaft 37 and adapted, when the blower is in operation, to be lifted up against a stop 40, conveniently in the form of the head of a screw carried on the upper end of the rod 37. The rod can be adjusted by turning the thumb wheel at the bottom and locked in place by the nut 40.

When the burner blower is in operation the air passing through the ports escapes around the periphery of the disk 39 and enters inside

an air diffuser 41. As here shown this air diffuser is of generally conical shape and has a row of openings 42 at the bottom to discharge air out below the wick tube and other openings 43 to discharge air into the interior of the wick tube. The air will pass up between the wick tube and the collar 32 and up through the flame spreader to support combustion when the burner is lighted. When it is not lighted the air escapes. Should the fan stop because of current failure or from mechanical difficulties, or should the voltage drop too low to supply enough air to support proper combustion, the valve member 39 will drop, sealing the air chest against the admission of fresh air, and this will quickly extinguish the flame. Inasmuch as all the burners connected to the conduit will have similarly functioning air valves, it is apparent that all the valves will be closed and air cannot be drawn in through one burner, passed through the conduit, and discharged through the lighted burner.

In the arrangement shown in Figures 4 and 5 the upper wall of the conduit 11 is provided with a large opening 44 below the wick tube and this opening is closed by a plate 45 having notches 46 adapted to register with clips 47 so that the plate 45 can be secured to the top of the conduit, or released from it. The plate 45 carries ports 48 similar to the ports 38 and a valve mechanism 49 similar to that shown in Figure 2. A slightly different form of air diffuser is indicated at 50. The plate 45 is connected with the flame spreader 34 by straps 51 so that when one removes the flame spreader, the air valve and associated air diffuser is also removed. Where the flame spreader is of the type having an electric igniter means, the current supply wire 52 may be connected to a blade 53 cooperable with a fixed contact 54 so as to connect and disconnect the ignition coil incident to the insertion 40 and removal of the flame spreader. This makes it possible to clean these parts at the same time that one cleans the wick.

In the arrangement shown in Figures 6 and 7 the wick tube, wick, flame spreader and air chest may be similar to what has been above described and corresponding reference characters have been applied. Here the air chest has a lower stamping 60 to which is secured the housing 61 for a motor 62. This motor has a vertical shaft and operates an impeller 64. The air is drawn in through ports 65 past a valve member 66 similar to the one previously described. The air is discharged from the blades of the impeller 64 and received within a deflector 67. Some of the air is passed out under the wick tube, as shown, and another portion of the air passes under the deflector 67, as indicated, so that the air enters the air chest comparatively free of turbulence. In this arrangement it will be noted that the self-closing valve is inside the motor housing and controls the inlet port for the single burner. Such a valve is entirely satisfactory for a single burner, as there is no possibility of one burner drawing in air from another.

It is obvious that the invention may be embodied in many forms and constructions within the scope of the claims and I wish it to be understood that the particular forms shown are but a few of the many forms. Various modifications and changes being possible, I do not otherwise limit myself in any way with respect thereto.

What is claimed is:

1. A liquid fuel stove comprising a wick-type burner, a blower for blowing air to the burner

5 to maintain combustion at the surface of the wick under forced draft, and an air valve past which air must pass to supply the burner, the valve being maintained open by the pressure reaction of the moving air and being quickly self-closing in response to loss of said pressure reaction upon the cessation of said forced draft to immediately discontinue the supply of air from the blower to the wick surface and consequently extinguish the burner flame.

10 2. A stove such as claimed in claim 1, having a plurality of burners each provided with a similar air valve, all of which valves are maintained open by the blower, and each of which valves closes on cessation of forced draft whereby it is impossible for one burner to receive air carried downwardly through another burner.

15 3. In a liquid fuel burner, a blower adapted to create a forced draft, a conduit for conducting air from the blower, and having an outlet port, an air chest forming member extending upwardly from the conduit and into which air may pass from the port, a coaxial burner collar at the top of the air chest forming member, a wick type burner in the air chest and surrounded by the collar so that all air for combustion must pass through the port, and a valve member cooperative with the port to maintain the air passage open when the blower is in operation and quickly self-closing in response to cessation of said forced draft to immediately discontinue the supply of air from the blower to the wick surface and consequently extinguish the burner flame.

20 4. A burner such as claimed in claim 3, having air baffling means on the discharge side of the air valve to effect a diffusion of the air into the air chest.

25 5. In a liquid fuel burner, a source of air under pressure above atmospheric, a conduit connected thereto and having an outlet port, a valve member having a limited amount of vertical movement and adapted to close the port when the excess pressure above atmosphere is absent and to open the port when the excess pressure is applied, a diffuser above the valve member through which all the air from the port is discharged, an upwardly extending air chest about the diffuser and terminating in a burner collar, and a coaxial annular wick tube, wick and flame spreader in the air chest and extending to the top of the collar and adjacent the diffuser so that the air passing through the diffuser may be distributed both inside and outside the wick tube.

30 6. A burner such as claimed in claim 5, wherein in the flame spreader, the valve member and the diffuser are interconnected and upwardly removable through the wick tube as a unit.

35 7. A burner such as claimed in claim 5, wherein the port is in a disconnectible portion of the conduit wall, and said portion, together with the valve member and diffuser, are connected with an upwardly removable flame spreader.

40 8. The improvement in a liquid fuel stove employing a tubular wick, a double walled wick tube in which the wick is placed and a flame spreader above the wick tube and extending over the wick in spaced relation thereto, which improvement comprises an outer coaxial collar about the upper part of the wick tube and terminating close to the flame spreader, a wall extending downwardly from the collar and forming an air chest, a blower including a motor housing below the wall and having an inlet port, 45 an impeller mounted on a vertical shaft and

enclosed in the housing for drawing air in through the port and discharging it radially into the air chest, and a deflector intercepting the discharged air and disposed to discharge part of this air into the lower end of the wick tube and the remainder into the space about the wick tube.

9. The improvement in a liquid fuel stove employing a tubular wick, a double walled wick tube in which the wick is placed and a flame spreader above the wick tube and extending over the wick in spaced relation thereto, which improvement comprises an outer coaxial collar about the upper part of the wick tube and terminating close to the flame spreader, a wall extending downwardly from the collar and forming an air chest, a blower including a motor housing below the wall and having an inlet port, an impeller mounted on a vertical shaft and enclosed in the housing for drawing air in through the port and discharging it into the air chest, and a valve member over the inlet port, the valve member quickly opening in response to blower operation and immediately automati-

cally closing on cessation of blower operation to immediately discontinue the supply of air from the blower to the wick surface and consequently extinguish the flame.

10. A liquid fuel stove having a plurality of wick type burners each adapted to maintain combustion by natural draft whenever the bottom of the burner is in communication with a supply of air, a conduit for supplying air to all of said burners, a blower to supply air under pressure to the conduit, and self-closing blower openable means adjacent each burner and between it and the conduit whereby air under pressure may be supplied to all the burners irrespective of whether the burners are lighted and acting on cessation of blower operation to immediately and simultaneously discontinue the supply of air from the blower to all the wick surfaces as well as natural draft through such burners as are lighted and consequently extinguish the flames of said lighted burners whereby no burner can create a natural draft by drawing air in through another burner.
